Inventor

Florence B. Sterman

UNITED STATES PATENT OFFICE

108,408

DESIGN FOR A TEXTILE FABRIC

Florence B. Sterman, New York, N. Y.

Application December 27, 1937, Serial No. 73,889

Term of patent 7 years

To all whom it may concern:

Be it known that I, Florence B. Sterman, a citizen of the United States of America, residing in New York city, State of New York, have invented a new, original, and ornamental Design for a Textile Fabric, of which the following is a specification, reference being had to the accompanying drawing, forming part thereof, wherein, the figure is a plan view of a piece of textile fabric showing my new design.

I claim:

The ornamental design for a textile fabric, substantially as shown.

FLORENCE B. STERMAN.
